UNITED STATES PATENT OFFICE.

LEVI J. GROOM, OF NEW YORK, N. Y., ASSIGNOR OF TWO-THIRDS TO
THOMAS D. STETSON, OF SAME PLACE.

BATH AND WASH TUB.

SPECIFICATION forming part of Letters Patent No. 289,345, dated November 27, 1883.

Application filed March 8, 1880. (Model.)

To all whom it may concern:

Be it known that I, LEVI J. GROOM, a citizen of the United States, residing in New York city, in the county and State of New York, have invented certain new and useful Improvements relating to Convertible Bath-Tubs and Stationary Wash-Tubs, of which the following is a specification.

I equip a set of stationary wash-tubs with cocks and pipes so arranged that they may serve as independent wash-tubs, as usual, and also that on removing the partition the long vessel may be used as a bath-tub. I provide a removable partition, engaging in a corresponding shallow groove or recess in the sides, with a packing of rubber or other material adapted to make a tight joint, and I surmount this with a cross-bar of equal width, so connected by a screw that the cross-bar, being held down at each end, may serve as an abutment to strongly force down the partition and hold both the cross-bar and the partition very rigidly in place. The cross-bar thus firmly held is an efficient support for a wringer, which may be clamped on in the ordinary way. I equip the tub with a strong metal strap extending under the tub in the plane of the partition, and extending up each side nearly or quite to the top. I provide each end of such strap with a link adapted to strongly engage the corresponding end of the cross-bar, and to be turned down out of the way when the cross-bar and its connected partition are removed. The tubs may be provided with the ordinary covers applying over the spaces between the cross-bar or ends of the tub. My convertible device may be mounted in the ordinary position to serve as a wash-tub, and may serve that use with all the convenience of the ordinary stationary wash-tubs. It may be used in the kitchen of large houses, but is more especially adapted for the style of dwellings commonly known as "French flats," or the better class of tenement-houses, where a small room is or may be especially appropriated for a wash-room and bath-room.

The accompanying drawings form a part of this specification, and represent what I con-

sider the best means of carrying out the invention.

Figure 1 is a front elevation, partly in section. This view shows one of the covers raised. Fig. 2 is a longitudinal vertical section. In this view both covers are closed. Fig. 3 is a cross-section through the middle of the removable partition.

Similar letters of reference indicate corresponding parts in all the figures.

A is the body of the tub, supported on stout legs A', and re-enforced at its mid-length with additional wood, A'', presenting a rounded contour.

B is a strap of galvanized wrought-iron or other suitable material, applied to the exterior of the wood A'', and equipped at each end with a hinged ring or link, B' B''. The interior of the tub at the mid-length is grooved up and down each side, as indicated by a.

D is a removable partition adapted to match in the grooves a and divide the tub or vessel into two parts. It is provided on its upper edge with smooth pins or uprights D', and also with a stout nut, D'', firmly held by screws D', or other suitable means.

E is a stout cross-bar having holes receiving the pins D', and capable of rising and sinking thereon.

G is a screw engaging in the nut D'', and turning freely in the cross-bar E, which latter is held between collars on the screw, as shown.

G' is a crank or lever adapted for turning the screw.

The ends of the bar E overhang the tub at the front and rear, and are adapted to be engaged and liberated according as the links B' are operated. The link B' at the back should be narrow, to turn freely between the covers P. The corresponding end of the cross-bar E should be proportionally narrow. The front end of the bar and the front link may be wider.

To remove the partition, the screw G is operated to lower the bar which sets free the links B' B'', and the latter are then turned down by hand, and the partition D, with its attached cross-bar E and screw G, is removed by simply lifting. The vessel may then be

conveniently used as a bath-tub. To again adapt the vessel for washing, the partition D is inserted in the proper position, taking care to put the narrow end of the bar at the rear, 5 and after engaging the links B' on their respective ends of the bar E the screw G is turned to raise the bar strongly, thus forcing the partition down and holding all very rigidly. Care being taken to leave the lever G' 10 parallel with the cross-bar or to remove it altogether, the cross-bar E may receive and support a wringer, which may be used with the ordinary effect.

Modifications may be made in many of the 15 details without departing from the principle or sacrificing the advantages of the invention. I can pack the edge of the partition with rubber or other suitable material, to aid in making a tight joint. I can use more than one 20 partition D, and thus divide the vessel into more than two tubs. In such case I would provide corresponding sets of straps B, and connections for confining the several partitions. The grooves *a* may be of rounded section, and the edges of the removable partition 25 be correspondingly formed. I believe the device may serve successfully with the grooves *a* very shallow.

I propose in some cases to make the vessel

zinc-lined, and to form the lining with but a 30 shallow groove, or with two shallow grooves, of little width along the proper lines to receive the partition. The great force with which the partition may be forced down aids in holding the partition reliably without depending 35 much on the grooves. I believe that the grooves *a* may be dispensed with altogether, other reliable marks being provided to determine the position of the partition.

I claim as my invention—

1. The removable partition D and screw G, for forcing the said partition strongly down to form a tight contact with the body, in combination with said body A, as herein specified, for the purposes set forth.

2. The strap B and rings or links B' B', in combination with the body A, and with the removable partition D, cross-bar E, and screw G, arranged for joint operation as herein specified.

In testimony whereof I have hereunto set my hand, this 2d day of March, 1880, in the presence of two subscribing witnesses.

LEVI J. GROOM.
